2 SHEETS—SHEET 2.

UNITED STATES PATENT OFFICE.

DAMASE JACQUES, OF DETROIT, MICHIGAN.

RELEASING DEVICE.

1,079,297.

Specification of Letters Patent. Patented Nov. 18, 1913.

Application filed January 25, 1913. Serial No. 744,119.

To all whom it may concern:

Be it known that I, DAMASE JACQUES, a citizen of the United States, residing at Detroit, in the county of Wayne and State of Michigan, have invented certain new and useful Improvements in Releasing Devices; and I do hereby declare the following to be a full, clear, and exact description of the invention, such as will enable others skilled in the art to which it appertains to make and use the same:

This invention relates to releasing devices, and it more particularly relates to an improved form of releasable support.

15. The primary object of this invention is to provide a simple and thoroughly efficient supporting element in connection with and auxiliary to the usual supporting means for life boats.

20. Another object of the invention is to provide a device of this character in the form of an opening link which consists of several pivotally connected sections or elements provided with locking means and associated 25 with means for actuating the locking means for unlocking the same and simultaneously opening the link.

Another object of the invention is to provide a device of this character which may be 30 opened instantaneously, so as to instantaneously release a load which is carried or supported thereby.

Another object of the invention is to provide a device of this character which may be 35 quickly closed and automatically locked.

Another object of the invention is to provide means whereby the link may be unlocked and opened by a person who is at the time remote from the link and the weight 40 supported thereby; so as to provide the maximum of convenience and safety for the operator.

Another object of the invention is to provide a device of this character of maximum 45 strength consistent with minimum weight, and which is of maximum efficiency consistent with simplicity of construction and comparative inexpensiveness of manufacture and maintenance.

50. Another object of the invention is to provide a device of this character which may be operated by a child or other inexperienced person; and, another and very important object of the invention is to provide a device of this character which insures the maximum

of safety to the load carried thereby and to the operator.

While I have defined this invention as being primarily designed for supporting life boats, it is to be understood that it is by no means limited to such use, but may be employed for supporting building materials; buckets in mines, quarries and other excavations; cars, trucks, etc., in loading ships and barges; and in factories, furnaces; or in any place or for any purpose wherein it is desirable to quickly connect and disconnect the load which is to be suspended or carried. This device is also applicable for connecting cars with engines or motors, or for connecting wagons or other conveyances to traction engines, automobiles or other motive power, so that the vehicle being drawn may be instantaneously released and stopped at a predetermined point, while the tractor continues to move.

Other objects and advantages may be recited hereinafter and in the claims.

In the accompanying drawings, which supplement this specification, Figure 1 is an elevation view of my improved opening link applied to one end of a life boat and suspended from a pulley block. Fig. 2 is an enlarged side elevation view, partly in section and partly broken away. Fig. 3 is a view similar to Fig. 2, except that the broken element in Fig. 2 is entirely removed from the latter figure which is shown in open position. Fig. 4 is an edge elevation view, as seen from the left-hand side of Figs. 1, 2, 3, and 5. Fig. 5 is an enlarged view of a slightly modified form of the invention in connection with a pulley block. Fig. 6 is a fragmental detail view of a portion of the structure shown in Fig. 5. Fig. 7 is a view of the same structure shown in Fig. 6, the several elements being in opening position. Fig. 8 is a perspective detail view of the locking member or tumbler used in this modified form. Fig. 9 is a side elevation view of the tumbler; and, Fig. 10 is a rear elevation view thereof.

In these drawings, in which similar reference characters correspond with similar parts, throughout the several views; the boat 5 and pulley block 6 are illustrated merely for the purpose of demonstrating the mode of applying the device which constitutes my invention, and this device comprises a rectangular frame or link 7 which consists

of an L-shaped basal element 8, a pair of link elements 9, a pair of lock supporting bars 10, a lock-bar 12, a tumbler 13 and an operating lever 14. The bars or links 9 and 10 are normally in vertical position, while the lower element 8' of the L-shaped member 8 and the lock-bar 12 are normally in horizontal position, so that when in operation (as shown in Fig. 1), the bars 9 and 10 bear the tensile stress, while the bars 8' and 12 constitute supporting beams which engage the weight-connection 14^a and support-connection 15, respectively.

The elements 8 and 10 are rigidly secured together by means of rivets 16, so that they constitute an L-shaped member having its upper end bifurcated or provided with a slot 17 in which the tumbler 13 is pivotally mounted; said tumbler being formed with 20 trunnions 18 which extend through apertures or bearings in the members 10, as indicated by dotted lines at 19 (Fig. 4). The slot 17 extends a sufficient distance below the tumbler to allow the entrance of the relatively thin extension 20 of the lock-bar 12 which is provided with a shoulder 21, adapted to abut against the inner edges of the bars 10, so as to limit the closing movement of the link. The bars 9 are pivoted at 22 to the element 8', the upper ends of said bars 9 being pivoted at 23 to the lock-bar 12, so that said lock-bar may be moved longitudinally, and also swung upwardly on the pivot 23, (see Fig. 3). The bar 12 is also provided with shoulders 24 which contact with the inner edges of the bars 9, so as to limit the downward movement of the lock-bar 12, whereby the extension 20 is guided into the slot 17, under and into engagement with the tumbler 13. This tumbler is provided with a concaved surface 25 which slides over the convexed end 26 of the extension 20 when the latter is entering the slot, so as to rotate the tumbler and bring its detent 27 into the notch 28. The extension 20 has its upper surface convexed at 29, and fits against a concaved surface 30 of the tumbler. The bars 10 are preferably of steel or other springy material, so that the upper ends 50 thereof may be slightly separated, and will thereafter return to their normal parallel relation with each other. The inner surface of each bar 10 is provided with a small depression 31, these depressions being oppositely disposed and adapted to receive bosses 32, which are preferably hemispherical, these bosses being formed on opposite sides of the tumbler, so that when the tumbler is forced into its normal operative position, 60 it is held in that position by engagement of the bosses 32 and depressions 31.

One of the trunnions of the tumbler has a lever 14 securely and non-rotatably fitted thereon, this tumbler being preferably 65 squared at 18' and screw-threaded at 18^a, as

shown in Figs. 8, 9 and 10. The lever 14 may be operated by grasping its free end and pulling it downward, so as to rotate the tumbler 13 but I preferably provide a flexible member 33, secured to the free end of said lever 14 and extended to a point remote from the opening link, so that an operator may grasp the end or any intermediate portion of this flexible member and pull the lever down, in an obvious manner.

I may provide an eye or other suitable guide 34 through which the flexible member extends, so that the pull of the flexible member exerts a downward pull on the lever regardless of the direction in which the main portion of the flexible member is pulled. It is also obvious that the lever may be swung relative to the rigid element for disengaging the locking elements regardless of the position which the opening link has attained. For instance, as shown in Fig. 1, it may be assumed that the opening link has descended until it lies flat upon the deck or platform of the boat, and when the flexible element 13 is pulled, the end of the lever 14 is swung in the direction of the eye 34, so as to effectually move the tumbler and push the locking bar out of engagement therewith from between the furcations of the rigid member.

In operation, assuming that a load is being supported by the opening link, and it is desired to release the load instantly, it is only necessary to pull down the free end of the lever 14 (as described), thereby rotating the tumbler, so that the detent 27 pushes the lock-bar 12 longitudinally and disengages its extension from the slot 17. During this movement of the lock-bar, the detent 27 and notch 28 pass under the pivotal center of the trunnions 18, and the point 35 contacts with the concaved surface 25 to the right of the trunnions 18, so that the weight carried by the opening link causes such relative movement of the tumbler and lock-bar that the convexed surface 26 slides on the concaved surface 25, while the free end of the lock-bar 12 swings upward relative to the bars 9, into the position shown in Fig. 3, whereby the engagement of the bar 12 and element 15 is instantly released, so that the load is allowed to drop, or to remain at rest, according to the attending circumstances. The lower surface of the lock-bar 12 and the upper surface of the element 8' are preferably curved, as shown, so that the elements 14 and 15 will be automatically guided to the medial portions, respectively, of these bars.

It is obvious that for supporting a boat, it is preferable to employ one of these opening links at each end of the boat, and a single flexible element 13 may be connected with both of the levers 14, so that both of the links may be opened simultaneously by pulling the flexible member laterally at its

medial portion, so as to pull its end portions in opposite directions; although, if desirable, one of the opening links may be opened in advance of the other.

5 In the modified form shown in Figs. 5 to 10 inclusive, the links 9, locking bar 12 and elements 8 and 8' may be identical with those illustrated in Figs. 1 to 4 inclusive, but instead of the depressions 31, I provide 10 hemispherical bosses 32', while instead of the bosses 32 on the tumbler, I provide hemispherical depressions 31', and from these depressions to the concaved surfaces 30 and 30', I provide an arcuate groove 31^a, 15 which is of slightly greater depth at its outer end than the radius of the hemispherical bosses 32', and of slightly less depth adjacent to the depressions 31' than the latter, so that as the tumbler 13' rotates, the ends 20 of the bars 10' are gradually separated by the cam action of the converging arcuate groove 31^a, until the bosses 32' snap into the depressions 31', for holding the tumbler 13' in its normal operative position. This modified 25 form is especially applicable for links of this character which are designed to carry very heavy loads, and hence, the bars 10' are necessarily more rigid and less easily separated than the bars 10. The lever 14' in this 30 modified form is somewhat different in shape from the lever 14, and obviously, these levers may be reversed, and they may be set at either of several different angles on the polygonal portion 18' of the trunnions 35 18, to suit the attending circumstances and conditions.

It will be seen that I have provided a device of this character which is fully capable of attaining the foregoing objects, in a thoroughly practical and efficient manner.

40 I do not limit my invention to the exact details of construction, arrangement and combination of parts, as therewith illustrated and described, but my invention may 45 only be limited by a reasonable interpretation of the claims.

I claim:—

1. A releasable supporting link consisting of several elements movably connected to

gether, one of said elements being formed 50 of springy material and having a slot into which an end of another of said elements is adapted to be seated, locking means for normally securing said end in said slot, means engaging the wall of said slot for retarding 55 the movement of said locking means, and means whereby the locking means may be actuated for disengaging said end from said slot.

2. A releasable supporting link consisting 60 of a bifurcated member, a lock-bar having one end seated between the furcations of the bifurcated member, means movably connecting the other end of the lock-bar with the bifurcated member, a tumbler mounted between said furcations, and means for rotating the tumbler and thereby bringing it into locking engagement with said lock-bar, said furcations being of springy material and being provided with means for engagement 70 with the tumbler for retaining it in its normal operative position.

3. A releasable supporting link consisting 75 of a slotted element, a lock-bar, means pivotally connecting the lock-bar with the slotted element, said lock-bar being provided with means for guiding it into the slot of the slotted element and with means for limiting its movement into said slot and with a notch 80 and a convexed end portion adjacent to the notch, a locking member provided with trunnions and being thereby pivotally mounted within the slot and having a detent in engagement with said notch of the lock-bar, and with a concaved surface adapted 85 to contact with the convexed end of the lock-bar, whereby the lock-bar may be moved into contact with the locking member for rotating it and thereby moving the detent into and out of engagement with the notch. 90

In testimony whereof I have signed my name to this specification in the presence of two subscribing witnesses.

DAMASE JACQUES.
